United States Patent Office.

JAMES C. WALTER, OF NEW YORK, N. Y.

Letters Patent No. 65,780, dated June 11, 1867.

IMPROVED APPARATUS FOR HARDENING AND TEMPERING WIRE.

The Schedule referred to in these Letters Patent and making part of the same.

TO ALL WHOM IT MAY CONCERN:

Be it known that I, JAMES C. WALTER, of the city, county, and State of New York, have invented certain new and useful improvements in Apparatus for Hardening and Tempering Wire and other articles; and I do hereby declare that the following is a full, clear, and exact description of the same, reference being had to the accompanying drawings, making a portion of this specification, in which—

Figure 1 is a plan view of an apparatus constructed according to my invention.

Figure 2 is a central vertical longitudinal section of the same.

Similar letters of reference indicate corresponding parts in both figures.

This invention is designed for holding umbrella and parasol stretchers, or saws, or other like articles, in a straight position, while they are being hardened and tempered, thereby effectually preventing the same from warping during such hardening and tempering operations.

The invention consists in a straining-frame so constructed that the stretchers or other articles may be clamped therein and subjected to a longitudinal strain in such manner that the object mentioned is effectually accomplished, at the same time that the aforesaid articles may be very conveniently handled or manipulated, as required in the operations specified. The invention also consists in certain novel arrangement of parts whereby the articles are readily secured and retained in the straining-frame, and whereby the tension exerted upon the articles held in the said frame is rendered continuous, and whereby, furthermore, such tension may be adjusted at pleasure.

To enable others to understand the nature and construction of my invention, I will proceed to describe it with reference to the drawings.

A represents a rectangular metallic frame, furnished at one end with a shank or extension, A*, which is made tubular for the greater portion of its length, as shown at a. The two sides of the frame A are formed with guides b, which receive the ends of a sliding-head, B, arranged transversely in the said frame. This head B is constructed with a longitudinal groove at c, in which is placed any number of suitable square blocks, d, between which the inner ends of the articles to be hardened or tempered are clamped, as hereinafter fully set forth. The said blocks are retained in the groove mentioned by a top plate, e, secured upon the upper side of the head in the position shown more clearly in fig. 2, and are compressed and forced toward each other, when required, by means of two screws, f, passing through the ends of the head, as represented in fig. 1. Working through the outer end of the tubular portion a of the shank A*, is a screw, C, to the inner end of which is attached a strong spiral spring, D, the opposite end of which is connected by a link or hook, g, with the sliding-head B.

In using the apparatus in hardening and tempering parasol stretchers, indicated at a* in the drawings, which are provided with transverse holes at one end only, the perforated ends thereof are passed through suitable slots in the outer end of the frame A, and a transverse rod, h, is passed through the aforesaid holes in the ends of the frame, as shown in fig. 1, and the opposite or inner ends of the stretchers are placed between the blocks d, which are compressed to tightly clamp the said ends by means of the screws f. The stretchers being thus secured in the apparatus, the screw C is turned to draw upon the spring D, and consequently upon the head A, thus exerting a strain or tension longitudinally upon the stretchers, the degree of such tension being adjusted by the aforesaid screw C, while the spring D causes the same to be continuous. The frame A, with the stretchers a*, thus secured therin, is placed in a suitable furnace, and the stretchers are heated to the degree required in hardening or tempering the same, as the case may be, and being kept constantly strained during such heating operation, are effectually prevented from warping while undergoing the same. Furthermore, inasmuch as the extension A* serves as a handle, the apparatus may be very conveniently manipulated when in use. In removing the articles from the apparatus, the hook g is detached from the spring D, thus releasing the strain upon the said articles, which are then released from the clamping-blocks d by turning outward the screws f.

In operating upon umbrella stretchers, which are perforated at both ends, the sliding-head B may be furnished with a rod corresponding to the rod h, to hold the inner ends of the stretchers in place thereon; and when the apparatus is employed in operating upon saw-blades or other like articles, the outer end of the frame

A should be furnished with clamping devices equivalent to those upon the head B, in order to properly hold in place the outer ends of such articles.

What I claim as my invention, and desire to secure by Letters Patent, is—

1. The combination of the screw C with the sliding-head B, and frame A, substantially as herein set forth for the purpose specified.
2. The combination of the tension-spring, the sliding-head, and the frame A, substantially as herein set forth for the purpose specified.
3. The sliding-head constructed with clamping-blocks d and tightening screws f, substantially as herein set forth for the purpose specified.
4. The arrangement of the screw C, tension-spring D, sliding-head B, and frame A, substantially as herein set forth for the purpose specified.

JAMES C. WALTER.
